UNITED STATES PATENT OFFICE.

AUGUST C. FONG, OF CHICAGO, ILLINOIS.

DESIGN FOR A SYRUP-PUMP HEAD.

SPECIFICATION forming part of Design No. 31,996, dated December 19, 1899.

Application filed November 22, 1899. Serial No. 737,961. Term of patent 14 years.

To all whom it may concern:

Be it known that I, AUGUST C. FONG, a citizen of the United States of America, residing at Chicago, in the county of Cook and State 5 of Illinois, have invented a certain new and original Design for Syrup-Pump Heads, of which the following is a specification.

My invention relates to a certain new and original design for syrup-pump heads, illustrated in the accompanying drawings, in which—

The design here shown consists of an up- 15 right cylindrical portion A, from one side of which extends a horizontal cylindrical portion B, terminating in a shorter upright portion C.

From the opposite side of the portion A extends a laterally and upwardly projecting arm D, terminating in a horizontal cylindrical portion E, adjacent to which is a disk-shaped extension F.

The essential portions of the design herein shown are comprised in a pump-head having the cylindrical portions A B C and the laterally and upwardly projecting portion D.

I claim as new and desire to secure by Letters Patent—

The design for a syrup-pump head herein shown and described.

AUGUST C. FONG.
